HEADREST FOR ARTIFICIAL RESPIRATORS

Francis T. Wallin, Brookline, Mass.

Application March 22, 1947, Serial No. 736,573

5 Claims. (Cl. 128—29)

1 This invention relates to an adjustable head-rest, such as may be used on an artificial respirator, or "iron lung," or the like.

Heretofore in head-rests used on respirators, it has not been possible to secure fine adjustments of the head-rest, and the use of several pillows or pillows of varying thicknesses have been necessary to secure suitable adjustment. Furthermore, in previous head-rests it has not been possible to lower the head-rest quickly, as is frequently required in emergency cases. Artificial respirators, of course, are used to provide artificial respiration where the patient is unable to breathe naturally, due to paralysis of the diaphragm, or injury to the respiratory nerve centers, as in cases of polio, electric shock, and various brain conditions, such as tumors, skull fractures, concussions and the like. In such cases it is not unusual for the patient's throat to suddenly fill up or close, and the patient will choke to death in a very few minutes unless relief is immediately provided. For this purpose the head of the patient must be lowered in the quickest time possible, and to permit emergency tracheotomy or bronchoscopy operations, a head-rest permitting such quick lowering of the head is most essential in such situations.

I have devised an adjustable head-rest to overcome the defects and objections of previous head-rests used on such apparatus, and which permits adjustments in height of the head-rest of as little as $\frac{1}{8}$ of an inch of height at a time or which can be dropped completely out of the way in two or three seconds' time whenever desired to permit emergency treatments and operations.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

Other advantages and objects will appear in the following specification and accompanying drawings, in which

Fig. 1 is a perspective view of the head-rest in its lowered position;

Fig. 2 is a perspective view of the same in its highest position;

Fig. 3 is a side elevation with parts in cross

section of the arm and winding mechanism thereon;

Fig. 4 is a side elevation of the attaching plate for the sling;

Fig. 5 is a sectional elevation of the locking means for the head-rest;

Fig. 6 is a perspective view of the locking collar, and

Fig. 7 is a sectional elevation of the same.

In the drawings 10 represents the end wall of a respirator and 11 represents the head aperture therein. Extending horizontally from the end wall 10 of said respirator, on opposite sides of the head aperture are two arms 12 and 13 forming supports for the head-rest. The arms 12 and 13 are preferably screwed into the end wall 10 by suitably threaded ends such as 13a on arm 13 (Fig. 3). A sling 15 of suitable flexible material, such as rubberized cloth, is provided, having a loop 16 in the fixed end thereof which is inserted over the arm 12. The other end is fixedly attached to a sleeve 20 by means of attaching plate 21, and screws 22 therein. Sleeve 20 in turn is rotatably mounted on arm 13. The arm 13 is shown in more detail in Fig. 3 and comprises the threaded end 13a, abutting nut 23 and threaded end 24 having collar 25 which is fixedly attached to threaded end 24 by means of screw 26. Collar 25 has radial holes 27 provided therein to receive locking pin 36 referred to below. The holes 27 can be spaced apart a suitable distance, depending upon the fineness of the adjustment desired for the head-rest.

The sleeve 20 encloses arm 13, being loosely mounted for rotation thereon and is shorter than arm 13, preferably by about $\frac{3}{8}$ of an inch. Sleeve 20 is held on arm 13 by means of the collar 25 on the outer end of arm 13 which abuts inner end wall 28 of said sleeve 20 (Fig. 3), and by nut 23 on the other end, and being shorter than arm 13, sleeve 20 is free to move longitudinally on arm 13 between these two abutments. Means is provided for turning said sleeve 20 for winding and unwinding the sling 15 thereon, which includes enlarged end 30 (Figs. 3 and 5), handle 31 and oppositely extending knob 32. Means for locking said sleeve 20 to said arm 13 is also provided, which includes radially extending bushing 35 (Fig. 5) having mounted therein pin 36 having head 37, flange 38 abutting lower interior edge 39 provided in enlarged end 30. Lower end 40 of said pin 36 is designed to enter radial holes 27 provided in said collar 25, being tensioned to enter said holes by means of spring 41. A loose

pillow 18 is provided to lie on the supporting surface of the sling 15.

The operation of the device is as follows: The arms 12 and 13 being firmly screwed into the end wall 10 of the respirator, sleeve 20 is inserted over arm 13 and firmly fixed thereon by means of collar 25 and screw 26. Attaching plate 21 has previously secured the loose end of sling 15 to sleeve 20 by means of screws 22. The loop 16 at the other end of sling 15 is then inserted over arm 12, and the sling is wound up on sleeve 20 or unwound by means of handle 31, by pulling out pin 36 and pushing sleeve 20 inwardly on arm 13 until the inner end of sleeve 20 abuts nut 23. Pin 36 is then unable to enter holes 27 in collar 25 and sleeve 20 may be rotated until the sling 15 is raised or lowered to the desired elevation. At the point of the desired elevation, the sleeve 20 is again pulled out, until inner end wall 28 of said sleeve abuts collar 25 on arm 13, allowing pin 36 to register with and enter holes 27 in collar 25, thereby locking the sleeve 20 to said arm 13, and holding the sling 15 in fixed position. When the head-rest is held in head supporting position, if an emergency arises requiring the head-rest to be lowered quickly, this is done merely by lifting the pin 36, pushing in the handle 31 of sleeve 20, and either unwinding sleeve 20 by turning handle 31, or placing the hand on top of the pillow 16 or sling 15 and pressing down, and the sling will thus drop down instantly out of the way.

It will thus be seen that I have provided an improved adjustable head-rest which permits fine adjustments in the height of the head-rest and which can be dropped down completely out of the way in a very few seconds whenever desired, to permit emergency treatment or operation on the patient.

I claim:

1. An adjustable head-rest for an artificial respirator or the like, including a pair of arms extending from the end wall of the respirator, a sling of flexible material supported at the ends thereof on said arms, a sleeve rotatably mounted on one of said arms and having the free end of said sling attached thereto, a handle on said sleeve for turning said sleeve to wind or unwind the sling thereon, and a series of circumferential holes on said sleeve arm and a pin cooperating therewith for releasably locking said sleeve to said arm to hold said arm and sleeve in fixed relation.

2. An adjustable head-rest for an artificial respirator or the like, comprising a pair of arms extending from the end wall of the respirator, a sling of flexible material supported at the ends thereof on said arms, a sleeve rotatably mounted on one of said arms and having the free end of said sling attached thereto, a handle on said sleeve for turning said sleeve to wind or unwind the sling thereon, a collar on said first arm having radial holes therein, and a spring-tensioned pin mounted in said sleeve adjacent said collar to engage the holes therein, for releasably locking said sleeve to said arm.

3. An adjustable head-rest for an artificial res-

pirator or the like, comprising a pair of arms extending from the end wall of the respirator, a sling of flexible material supported at the ends thereof on said arms, a sleeve rotatably mounted on one of said arms and having the free end of said sling attached thereto, a handle on said sleeve for turning said sleeve to wind or unwind the sling thereon, and means for releasably locking said sleeve to said arm to hold said arm and sleeve in fixed relation, and means for releasing said sleeve from said arm to permit winding and unwinding of the sling on said sleeve.

4. An adjustable head-rest for an artificial respirator or the like, comprising a pair of arms extending from the end wall of the respirator, a sling of flexible material supported at the ends thereof on said arms, a sleeve rotatably mounted on one of said arms and having the free end of said sling attached thereto, a handle on said sleeve for turning said sleeve to wind or unwind the sling thereon, a collar on said first arm having radial holes therein, and a spring-tensioned pin mounted in said sleeve adjacent said collar to engage the holes therein, for releasably locking said sleeve to said arm, said sleeve being shorter than said arm to permit said sleeve to be moved longitudinally on said arm, and thereby to hold said pin out of locking engagement with said collar, and permit said sleeve to rotate on said arm to raise or lower the head-rest.

5. An adjustable head-rest for an artificial respirator or the like, comprising a pair of arms extending from the end wall of the respirator on opposite sides of the head aperture thereof, a sling of flexible material fixedly supported at one end thereof on one of said arms and adjustably supported at its other end on the second arm, a sleeve rotatably mounted on said second arm, and having the free end of said sling attached thereto, said second arm having abutments on the ends thereof, and said sleeve being shorter than the distance between the abutments on said arm to permit said sleeve to be moved longitudinally on said arm, a handle on said sleeve for turning said sleeve to wind or unwind the sling thereon, radial holes provided in the outer abutment on said arm, and a spring-tensioned pin mounted in said sleeve adjacent said outer abutment to engage the holes therein, for releasably locking said sleeve to said arm, whereby when said pin is manually disengaged and said sleeve is pushed inwardly on said second arm, said pin is moved out of alignment with the holes in said outer abutment on said second arm, and said sleeve is free to be rotated on said second arm to raise or lower the head-rest.
